UNITED STATES PATENT OFFICE.

MOSES G. NORTON, OF LOS ANGELES, CALIFORNIA.

KEY-LOCK.

1,293,616.

Specification of Letters Patent.

Patented Feb. 4, 1919.

Application filed October 9, 1916. Serial No. 124,475.

To all whom it may concern:

Be it known that I, MOSES G. NORTON, a citizen of the United States, residing at Los Angeles, in the county of Los Angeles and 5 State of California, have invented certain new and useful Improvements in Key-Locks, of which the following is a specification.

This invention relates to improvements in locking devices for keys, and has particular 10 relation to means for holding a key in a lock, so that it cannot be removed therefrom by unauthorized parties, and so that it cannot be turned in the key hole for pushing it out, and further so that no one can insert an 15 instrument in the key hole while the lock is in place.

It is an object of the invention to supply a key lock provided with means for inclosing and positively holding the bow or handle 20 of a key and also having a key shank receiving means, and a key hole engaging portion.

It is also an object of the invention to provide a key lock made from a single piece of material and shaped to engage a key hole 25 and hold the key therein.

It is a further object of the invention to provide a key holding lock device having locking means adapted to fold over the bow of the key, locking means being also provided for grasping the bow or handle of the 30 key whereby the key cannot turn in the key hole or be removed therefrom.

It is still a further object of the invention to provide a key lock having means for gripping the bow of the key, an auxiliary lock 35 for preventing the disengaging of the device from the said key bow, whereby the key can be prevented from removal, whether the said key be located upon the inside or outside of 40 a door or lock.

With these and other objects in view the invention comprises certain novel constructions, combinations, and arrangements of parts as will hereinafter be more fully described and claimed.

In the accompanying drawing forming a part of this specification:

Figure 1 is a perspective view of the key lock forming the subject matter of this invention, showing the same applied to a key as when locked in a lock.

Fig. 2 is a vertical sectional view taken upon the line 2—2 of Fig. 1, the key being shown in side elevation.

Fig. 3 is a detail sectional view taken upon the line 3—3 of Fig. 2.

Fig. 4 is a perspective view of a key lock struck from a single piece of metal and folded or bent to the desired shape.

Fig. 5 is a transverse sectional view 60 through the head portion of the device shown in Fig. 4.

Fig. 6 is a plan view of a blank as struck from a single piece of metal, in readiness for producing the key lock shown in Fig. 4. 65

Fig. 7 is a perspective view of a modified form of lock made from a piece of wire and adapted to be latched upon opposite sides of the key bow.

Fig. 8 is a perspective view of another 70 modified form of key lock, but showing jaws adapted to be sprung upon the opposite edges of the key bow.

The device of the present invention is designed to afford simple means for holding 75 a key within a lock, so that the key cannot be removed and cannot be turned so as to unfasten the lock. The device is also capable of holding the key so that it cannot be removed by unauthorized parties, either 80 from the outside of a door or from the inside thereof, that is to say the key is secure in the lock whether it can be reached from the key side or from the other side of the lock or door.

The details and features of the invention will now be more particularly described, reference being had to the accompanying drawing, in which practical embodiments of the invention have been disclosed. In said 90 drawing in which 5 indicates a key bow engaging a plate, 6 a key hole engaging and filling portion, and 7 a plate for clamping the bow or handle of the key in position on said plate 5. The plate 5 may be made 95 integral with the key hole portion 6 and the connecting portion between the two parts may be folded upon itself to form standards or key engaging projections 8. A space at 9 is cut away at the central portion of said standard to form a recess to receive the stem 10 of a key. The portion forming the key hole engaging portion 6 is preferably folded upon 100 itself to give a double thickness at 4 to the portion which extends into the key hole whereby it is given a proper width to substantially fill the key-hole and also a proper stiffness to prevent the inserting of tools and implements of any kind for acting upon the key in any way. The locking piece or 105 member 7 may be hinged at 11 to the outer edge of the plate 5, and it is preferably bent

110

at 12 so that the body portion of said member may extend parallel with the plate 5 over the bow 13 of the key 14.

The locking plate piece or member 7 may 5 carry a key operated lock 15 by which it may be locked in position for preventing the manipulation of the inclosed key in any way. The said plate is usually provided with slots or apertures 16 adapted to fit 10 over the ends of the standard or projections 8. The lock 15 may be of any desired type and it is provided with one or more bolts 17 adapted to be shot into apertures 18 formed in the standard 8 for holding the 15 parts together. The locking member of piece 7 can thus be held so that it cannot be opened by unauthorized parties. The lock 15 is preferably of a flat type which will not require a great deal of room within the 20 locking piece or member 7, and can only be operated by a person having a key that will fit the lock. A key-hole 19 in the member 7 permits the insertion of a key for operating the said lock 15. While the lock may 25 have only a single locking bolt, on account of the dividing of the standard 18 to provide the recess 9 for the key, there may be two bolts 17 as shown in Fig. 3 of the drawing, there being two recesses or keeper sockets 30 18 in this instance to receive the bolts 17. It should be understood that the particular way in which the lock is mounted may be varied without departing from the spirit of the invention and that the lock 35 may be placed upon the member 7, or upon the plate 5, or arranged at the sides of the device so that the key may be applied for locking the device from the top or bottom or from any other direction as found most 40 desirable, without departing in the least from the spirit of the invention.

The key hole engaging member 6 is preferably in the form of a tongue being usually folded from the blank from which the device is made and being made of a suitable 45 length to extend into the key hole beneath the stem or shank of the key, and sufficiently far into the key hole to prevent the unauthorized turning of the key and the insertion 50 of tools or implements by which the key might be turned or operated in the lock, the plane of the tongue 6 is preferably at right angles to the plane of the plate 5, and therefore to the plane of the key bow 13, so that 55 the lock operating tang 20 will be prevented from being turned into the plane of the key hole when the key hole engaging portion or tang 6 is held in place in the said key hole. The outer end of the tang or portion 6 may 60 be tapered at 21 to facilitate its insertion in a lock, but the tapered portion is preferably not made sharp at the end, but is rounded at 22 to facilitate inserting in the key hole and to protect the hand of the operator 65 from possible injury.

Instead of making any portion of the key lock pivoted with respect to the remainder thereof as shown in Figs. 1, 2, and 3, the device may be struck from a single piece of material. Thus as shown in Fig. 4, the said key lock can be stamped from a single plate and bent to the desired form. In this case a blank like that shown in Fig. 6 is struck from the metal, said blank having an elongated wide portion 23 having apertures 24 and 25 cut therein, the latter of which when the blank is folded to form standards 26, affords space for the key receiving recess 27. The aperture 24 serves to lighten the blank and still provides for ample metal in the parts to grip the head or body of the key. This portion of the blank when bent becomes the key bow receiving means comprising a plate portion 28 and a sprung plate portion 29 with a connecting portion 30. The outer end of the board portion of the blank 23 may have patches 31 stamped from the metal thereof, the stamped portion being bent inwardly so as to engage under-cut or dove tailed notches or recesses 32 in the ends of the standards 26.

The plate 29 may be sprung inwardly over the bow of the key until the catches 31 engage the recesses 32 for holding the parts together. The blank 23 is also the right size in width for a portion of its length to provide the tongue or key hole engaging member of the device. This portion of the blank as shown at 33 is also shaped that it may be readily folded from the narrow neck 100 portion 34 outwardly along its median line for producing the key hole engaging portion 35 with its tapered point 36 and rounded end portions 37.

Instead of making the device of flat metal 105 the key lock may be formed of round metal or wire as illustrated in Figs. 7 and 8. As shown in Fig. 7 the wire may be bent or looped at 38 to form the key hole member or tongue, the wire being twisted at 39 to 110 form a neck of suitable strength to hold the head portion 40, and the key bow clasping portion 41. The head and the clasping portion 41 may be substantially rectangular in shape, the wire being usually crossed at 42 where the clasping portion 41 is connected with the head portion 40. At the inner corners of the head portion 40, loops 43 are provided, into which projections 44 on the outer free corners of the clasped portion 41 115 are sprung to fasten the parts snugly upon the bow of the key.

A little different form of key may also be provided from wire as shown in Fig. 8, in which a single piece of wire is bent into the form of an elongated loop to provide a key hole engaging member 45. The wire at the inner end of the said member 45 is bent to form side jaws 46, 47 having parallel portions adapted to be sprung upon the oppo- 120 125 130

site edges of the bow of the key, the outer ends of said jaws being hook shaped to form locking end portions. One of the said locking end portions as 48 has outwardly bent 5 projecting portions or shoulders 49 to limit the inward movement of the hook 50 upon the other jaw. The end of the hook 48 outside the shoulder 49 is narrow enough to extend into the hook 50 of the other jaw. 10 These hooks may be readily separated, and after springing them over the edge of the key bow they may be hooked together as shown in Fig. 8. The stem of the key rests in a space 51 between the said jaws. If desired an auxiliary lock of any kind, as for instance, a pad lock may have its shackle passed around and through the hooks 48 and 50, for locking the device and preventing its 15 operation by unauthorized parties. 20 It will thus be evident that the key lock of this invention may be formed in several ways, without departing from the spirit of the invention.

It will be understood of course that in 25 either form of the device the key hole engaging member may be made of a piece of material struck up and shaped as shown in Figs. 1, 2, and 3, or of wire folded double as shown in Fig. 8, and that the jaws 46 30 and 47 may be used with either type of key hole engaging tongue as may be preferred.

What is claimed is:

1. A key lock of the character referred to,

comprising a key-receiving member having a portion adapted to be inserted with the key 35 into a key hole, and having a key-actuated locking mechanism adapted to inclose the bow of a key and to lock the key and the key receiving member together against unauthorized manipulation or removal of said 40 key from its lock, substantially as described.

2. In combination with a lock and key therefor, a key-locking device adapted to be inserted with said key into said lock, and having a part for inclosing the bow of a key, 45 and a key-actuated lock for locking said key-lock to said key, whereby to prevent the manipulation or removal of said key from its lock, substantially as described.

3. In combination with a lock and key 50 therefor, a key-locking device comprising a body having a portion adapted to be inserted with said key into its lock, and having a key-bow-receiving portion adapted to inclose the same to prevent the turning of said 55 key, and a key-actuated-locking means for locking said key-bow-receiving portion to said key-bow, whereby to prevent the removal or turning of said key in its lock.

In testimony whereof, I have hereunto set 60 my hand, in presence of two witnesses.

MOSES G. NORTON.
